DIRIGIBLE AIRSHIP

Karl P. Hilberth, White Plains, N. Y., assignor
of forty per cent to Samuel Steckler and
twenty per cent to Hyman Hecker, both of
White Plains, N. Y.

Application June 25, 1937, Serial No. 150,400

4 Claims. (Cl. 244—30)

This invention relates to an improvement in airships of the dirigible type and more particularly to the control of the airship both in the air and for vertical ascending and descending.

5 The object of the invention is to improve the control and steering mechanism, whereby the air from the engine propellers may be used for vertical movements of the airship, as well as for steering.

10 This may be accomplished by the provision of shiftable planes in alignment with the propeller axes, so that the air flowing from the propellers will be directed against these planes and act thereon for moving the corresponding portion 10
15 or portions of the airship up or down as may be desired, either to maintain the stability and levelness of the airship in flight, or for ascending or descending at an airport. The actuation by the air currents will depend upon the positions 20
25 of the planes, which must be adjusted by a pilot either together or individually, in order to maintain the desired position of the airship or to obtain a desired movement thereof.

Another object of the invention is to provide 25
25 for holding the airship against being blown by the wind during ascending or descending thereof, which is accomplished by the use of an additional motor and propeller at the stern which may be driven in an appropriate direction to hold the airship against the wind. The rudder 30
35 is associated also with this additional propeller so as to utilize the blasts of air therefrom in steering the airship during its flight or to a desired position at the airport. In fact, by this means, the airship may be turned substantially in a circle.

Still a further object of the invention is to prevent destruction of the body of the airship by a blast of air against the sides thereof, which 40
45 is accomplished by the provision of fins extending lengthwise on opposite sides of the body of the airship in positions to deflect the wind around the sides thereof, and prevent a side blast of air thereagainst which would act in an injurious manner thereon and might cause destruction of the body portion.

A preferred embodiment of this invention is set forth in the accompanying drawings, in which:

50 Fig. 1 is a perspective view of an airship embodying this invention;

Fig. 2 is a front end elevation thereof;

Fig. 3 is a side elevation thereof;

Fig. 4 is a bottom plan view thereof;

55 Fig. 5 is a diagrammatic side view showing the

planes in positions for descending of the airship; Fig. 6 is a similar view with the planes in positions for ascending; and

Fig. 7 is a diagrammatic perspective view showing the controls for the planes.

The body portion of the airship is designated generally by the numeral 1 and may be of any desired or well-known construction adapted to be filled with gas of a character to sustain the weight of the airship. The body portion 1 has a cabin 2, extending lengthwise of the bottom thereof throughout approximately one-half of the length of the airship being of greater length than the usual gondola, which cabin may provide suitable quarters or control rooms, and by having these below the bottom of the airship instead of within the same, the weight is more nearly stabilized. Any desired arrangement of supporting wheels 3 may be used for sustaining the airship on the ground.

20 The airship is propelled by engines 4 and 5, of any desired type, for operating propellers 6 and 7, which engines are of the reversible type and are mounted at opposite sides of the airship at the bottom thereof instead of being disposed at the bottom or adjacent the bottom in the arrangement usually provided.

25 Mounted on shafts 8 and 9, extending transversely of the body portion 1 and journaled therein for turning movement, are planes 10 and 11 on opposite sides of the airship. The planes 10 are mounted in front of the engines 4 and the planes 11 are mounted behind said engines, and the turning axes of said planes 10 and 11 are in horizontal alignment with the axes of the propellers 6. A set of planes 12 is also mounted at the rear of the airship on a shaft 13, extending transversely of the airship and journaled in the body thereof for turning movement about an axis, which is arranged in the same horizontal plane as the axes of the propellers 7.

30 The shafts 8, 9 and 13 are designed to be rotated for turning the planes to desired positions by suitable means, such as cables 14 extending to levers 15, pivoted in positions for manipulation by a pilot for individual control of the planes as may be desired to maintain the proper position of the airship in flight or for ascending or descending. The same pilot should have control over the engines 4 and 5 for actuating the same, not only for propulsion, but also for proper control of the airship in conjunction with the planes.

35 For steering, a rudder 16 is pivotally mounted at the rear of the airship beneath the bottom

thereof, which rudder is pivotally mounted on a vertical shaft 17, suitably stabilized to maintain its position with respect to the body portion 1. An engine 18 is mounted between the bottom of 5 the airship with a propeller 19, immediately in front of the rudder 16 and having its axis intersecting the vertical pivotal axis of the rudder. In this way, the operation of the engine 18 causes the propeller 19 to direct a blast of air against 10 the rudder 16, when turned to an angular position to assist in steering the airship in flight, and by this means the airship may be turned completely around in a circle or turned in such directions as may be desired, even when not in flight. The 15 engine 18 may be operated also to hold the airship against the wind when ascending or descending to prevent its drifting or being blown out of its position during such vertical movement or to hold it in a steady position over a desired 20 point.

Extending lengthwise along opposite sides of the body portion 1 are horizontal fins 20, each of which is approximately triangular in cross section, as shown in Fig. 2. These fins extend approximately throughout the length of the body portion, one on each side, and are arranged at the middle of said body portion in order to deflect wind blowing thereagainst around the sides of said body portion to prevent a strong blast of 30 wind directly against the side which might cause serious injury thereto. These fins 20 not only serve as wind breakers, but they also serve to reinforce the body portion 1 lengthwise thereof, and to provide additional gas chambers for increased lifting power.

The parts are shown in Fig. 1 in their normal positions during flight, in which the engines 4 and 5 are rotating the propellers 6 and 7 for propelling the ship forward. In this figure, all of the 40 planes 10, 11 and 12 are arranged horizontally, the propellers then serving merely to propel the airship through the air. Whenever it is necessary to increase the lift of the airship over that provided by the gas contained therein, this may be accomplished by tilting the planes 11 and 12 45 to the positions shown in Fig. 3, where the blast of air from the propellers 6 and 7 are directed against the undersides of these planes with sufficient force to increase the lift of the airship over that normally provided by the atmosphere. By increasing the tilt of the planes 11 and 12, the airship may rise during its travel and thereby attain a greater elevation, or these planes may be shifted to the opposite positions where the 55 blasts of air from the propellers are directed against the upper sides of the planes and thereby causes a descending of the airship in the course of its flight.

Due to variations in air and wind, it will be 60 necessary for the pilot to shift the planes 11 and 12 to different positions, and with respect to each other in order to maintain the airship on an even course and in a horizontal position, either raising or lowering the entire airship or either end thereof with respect to the other. The pilot also controls the rudder 16 to maintain the direction of flight which may be used alone or in connection with the engine 18 driven in a direction to direct a blast of air against one side or the other of the 65 rudder according to its angular position.

When it is desired to stop the airship during its flight and to descend, as, for instance, at an 70 airport, it will only be necessary for the pilot to shift the planes 11 to horizontal positions, to shift the planes 10 to the tilted positions shown

in Fig. 5, and to reverse the engines 4, (all of the engines 4 and 5 and 18 being of the reversible type) so as to operate the propellers 6 to direct blasts of air against the upper sides of the planes 10 as opposed to the air blast action of the propellers 7, against the upper sides of the rear planes 12 which are also in the positions shown in Fig. 5, being turned thereto, if necessary. In this way, the flight of the airship may be stopped and lowered to the ground, during which lowering 10 movement, the engine 18 may be operated in a direction tending to hold the airship against the wind and against travel in the air. For ascending, the planes 10 and 12 are shifted to the positions shown in Fig. 6, where the propellers 6 and 15 1 direct blasts of air against the underside thereof with sufficient velocity to apply lifting pressure to the airship at opposite ends, and the engine 18 may be operated also at this time, if 20 desired.

The engine 18 may be driven in a forward direction during flight of the airship to assist in its propulsion, but by being placed under the bottom of the airship, it acts together with the rear engines 5 to direct the flow of air therewith along with sufficient velocity to relieve substantially the usual vacuum or suction created by the forward motion of the airship through the air. By the use of the planes for ascending or descending by the power of the engines, it is unnecessary to throw out ballast or release gas for landing. In fact, the airship can be landed by its own power or manipulated into a hanger.

I claim:

1. In an airship, the combination of a body portion, power plants arranged at forward and rearward portions of said body portion and having propellers so constructed and arranged as to act respectively in opposite directions at the forward and rearward portions of the body portion, and planes arranged adjacent the propellers in positions for action of the propellers toward said planes, and means mounting each plane for turning movement about a transverse axis approximately intersecting the axis of rotation of the adjacent propeller and said plane being arranged with the propeller axis extending approximately through the mid portion thereof.

2. In an airship, the combination of an elongated lighter than air body portion, power plants arranged at forward and rearward portions of said body portion on each opposite side thereof and spaced apart a substantial distance, said power plants having propellers connected therewith and so constructed and arranged as to act respectively in opposite directions at the forward and rearward portions of each side of the body portions, a pair of planes arranged at the front and rear of each forward power plant in relatively close relation thereto and a plane adjacent the propeller of the rearward power plant, means mounting said planes for turning movement about transverse axes intersecting the longitudinal axes of the respective propellers, and means for adjusting the respective planes on each side of the body portion independently of each other for turning movement to different angular positions, whereby the propellers may be turned to angular positions relative to the air movement for elevating or lowering the airship or holding the same in flight.

3. In an airship, the combination of an elongated lighter than air body portion, power plants arranged at forward and rearward portions of said body portion on each opposite side thereof

and spaced adjacent opposite ends thereof, said power plants having propellers connected therewith and so constructed and arranged as to act respectively in opposite directions, whereby the propellers may be turned to angular positions relative to the air movement for elevating or lowering the airship or holding the same in flight at the forward and rearward portions, a pair of planes arranged at the front and rear of each forward power plant in relatively close relation thereto and a plane adjacent the propeller of the rearward power plant, means mounting said planes for turning movement about transverse axes intersecting the longitudinal axes of the respective propellers, each plane extending transversely equi-distances on opposite sides of the propeller axis thereof, the planes on opposite sides of the body portion being in axial alignment, and means for adjusting the respective sets of planes 20 on opposite sides of the body portion independently of other sets thereof for turning movement to different angular positions.

4. In an airship, the combination of an elongated lighter-than-air body, power plants on said body 25 and arranged at the forward and rearward por-

tions thereof at each opposite side thereof with the forward and rearward power plants spaced apart a substantial distance, each power plant having a propeller at one end thereof, the forward and rearward power plants having the propellers thereof facing respectively forwardly and rearwardly of the airship and operating in opposite directions, a plane mounted on the body at each side thereof forwardly of the forward power plant propeller, a second plane mounted on the body at each side thereof rearwardly of the rearward power plant, said planes being arranged at the same ends of the respective power plants as the propellers thereof and in close relation to the propellers, means mounting said planes on the body for turning movement about axes extending transversely thereof and approximately intersecting the axes of the propellers, and means for adjusting the respective planes on each side of the body to different opposed oblique positions in the 20 respective air paths of the propellers for alternative action on the respective upper and lower sides thereof by the air paths of the propellers to force the airship up or down.
